(57) **CLAIM**

We claim the ornamental design for a tray for washing machine, as shown and described.

DESCRIPTION

The file of this patent contains at least one drawing executed in color. Copies of this patent with color drawing(s) will be provided by the Office upon request and payment of the necessary fee.

FIG. 1 is a front perspective view of a tray for washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a second front perspective view thereof;

FIG. 9 is a third front perspective view thereof;

FIG. 10 is a fourth front perspective view thereof;

FIG. 11 is a fifth front perspective view thereof;

FIG. 12 is a sixth front perspective view thereof;

FIG. 13 is a seventh front perspective view thereof;

FIG. 14 is a cross sectional view taken through the line 14-14 of FIG. 9; and,

FIG. 15 is a cross sectional view taken through the line 15-15 of FIG. 4.

The color of the tray for washing machine forms no part of the claimed design.
